HOUSING FOR RAKE FOR FLUFFING CARPETS

Louis E. Kopecky, 4th and Downing Sts.,
Hollister, Mo. 65672

Filed Sept. 24, 1971, Ser. No. 183,747

Term of patent 14 years

Int. Cl. D7—05

U.S. Cl. D7—177

FIG.1

FIG.2

FIG.3

FIG.4

FIG.5

FIG. 1 is a top plan view of the housing for rake for fluffing carpets showing my new design;

FIG. 2 is a front elevational view thereof;

FIG. 3 is a right side elevational view thereof;

FIG. 4 is a left side elevational view thereof; and

FIG. 5 is a rear elevational view thereof.

The bottom of the device, not shown, is unornamented. The handle and prongs are shown in broken lines for illustrative purposes only.

I claim:

The ornamental design for a housing for rake for fluffing carpets, substantially as shown and described.
